UNITED STATES PATENT OFFICE.

JOHN PEARD, OF BROOKLYN, NEW YORK.

EVAPORATOR FOR HOT-AIR REGISTERS.

SPECIFICATION forming part of Letters Patent No. 247,682, dated September 27, 1881.

Application filed February 25, 1881. (No model.)

To all whom it may concern:

Be it known that I, JOHN PEARD, a citizen of the United States, residing at Brooklyn, in the county of Kings and State of New York, 5 have invented new and useful Improvements in Evaporators for Hot-Air Registers, of which the following is a specification.

My invention relates to that class of deflectors which are provided with water-tanks and 10 arranged over hot-air registers for the purpose of moistening the hot air prior to its escape into the apartment to be warmed.

The object of my invention is to provide simple and inexpensive devices for this purpose, 15 and to provide them with water-tanks which can be supplied with water from the exterior of the deflector, as required, without disturbing or removing the deflector.

This invention is illustrated in the accompanying drawings, in which, Figure 1 represents a horizontal section in the plane yy , Fig. 2. Fig. 2 is a vertical section in the plane xx , Fig. 1. Fig. 3 is a horizontal section in the plane zz , Fig. 2. Fig. 4 is a perspective view 25 on a smaller scale than the previous figures.

Similar letters indicate corresponding parts. In the drawings, the letter A designates my deflector, which is by preference made of sheet metal, but which can be made of any suitable 30 material. It is open at the bottom and made with an inclined top, a , a flat front, b , and two side flanges, $c c$, and of such a size that its inner edges fit closely against the wall which contains the hot-air register B, or against the 35 frame of said register.

In the example shown in the drawings my deflector is provided with legs $d d$, so that it can be placed over the register, as shown in Fig. 2; but the deflector may be made without 40 legs, and secured to the frame of the register by means of screws or other suitable fastenings.

In the interior of the deflector are secured two tanks, $C C'$, which are intended to be filled 45 with water. These tanks extend through the side flanges, $c c$, of the deflector, so that they can be conveniently supplied with water without removing the deflector from the register.

If desired, only one tank, C , can be used, and 50 this tank is placed at a slight distance from the front b of the deflector, so that the hot air which escapes from the register, on coming in contact with the inclined top a , is deflected down and brought in contact with the water

in said tank before it escapes at the open bottom end of the deflector, and thereby said air becomes charged with a sufficient quantity of moisture to deprive it of its noxious effects on the health of the persons occupying the room.

If the tanks $C C'$ are used, both may be placed 55 at a distance from the front of the deflector, so as to allow the heated air to circulate all round them or the lower tank, C' , may be placed close to the front b as shown in Figs. 2 and 3, and in this case I provide openings e in the front 60 b through which the heated and moistened air escapes.

My deflector is applicable to registers of fireplace heaters, or to registers of air-heaters situated in the cellar of a building and communicating with registers fitted into the walls of the different rooms.

It is obvious that the number of tanks in the deflector can be increased, if desired.

By reference to Fig. 2 it will be seen that the 75 lever for operating the valves of the register is situated beneath the tank C' in the deflector, so that the register can be opened or closed without difficulty.

What I claim as new, and desire to secure 80 by Letters Patent, is—

1. The deflector A for hot-air registers, constructed with an open bottom, flat front b , side flanges, $c c$, and the upper inclined end, a , joining and forming a continuation of the flat front 85 b , in combination with the horizontal water-tank having its ends held and supported solely by the side flanges, c , of the deflector to provide a clear open bottom to the latter for the free downward passage and escape of the vaporized hot air, substantially as shown and described.

2. The deflector A for hot-air registers, consisting of a front b , top a , and vertical sides c , in combination with a water-tank supported by 95 the sides, the said water-tank extending through one or both of the sides c , to provide for supplying the same with water from the exterior of the deflector, substantially as described.

In testimony whereof I have hereunto set my hand and seal in the presence of two subscribing witnesses.

JOHN PEARD. [L. S.]
